UNITED STATES PATENT OFFICE.

ELMER O. SIMONS, OF LOS ANGELES, CALIFORNIA.

DESIGN FOR A VASE.

42,402.

Specification for Design.

Patented Apr. 9, 1912.

Application filed October 5, 1911. Serial No. 653,028. Term of patent 3½ years.

To all whom it may concern:

Be it known that I, ELMER O. SIMONS, a citizen of the United States, residing in the city and county of Los Angeles, State of California, have invented a new, original, and ornamental Design for a Vase, of which the following is a specification, reference being had to the accompanying drawing, forming part thereof.

The figure is a view in elevation of a vase, showing my design.

I claim—

The ornamental design for a vase, as shown.

Signed in the city and county of Los Angeles, State of California, this 13th day of September, 1911.

ELMER O. SIMONS.
